(57) **CLAIM**

The ornamental design for a display screen with transitional graphical user interface for electric power socket track, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1.1 is a front view of a first image in a sequence for a display screen with transitional graphical user interface showing our new design;

FIG. 1.2 is a front view of a second image thereof;

FIG. 1.3 is a front view of a third image thereof;

FIG. 1.4 is a front view of a fourth image thereof;

FIG. 1.5 is a front view of a fifth image thereof;

FIG. 1.6 is a front view of a sixth image thereof;

FIG. 1.7 is a front view of a seventh image thereof;

FIG. 1.8 is a front view of an eighth image thereof;

FIG. 1.9 is a front view of a ninth image thereof;

FIG. 1.10 is a front view of a tenth image thereof;

FIG. 1.11 is a front view of an eleventh image thereof;

FIG. 1.12 is a front view of a twelfth image thereof;

FIG. 1.13 is a front view of a thirteenth image thereof;

FIG. 1.14 is a front view of a fourteenth image thereof;

FIG. 1.15 is a front view of a fifteenth image thereof;

FIG. 1.16 is a front view of a sixteenth image thereof;

FIG. 1.17 is a front view of a seventeenth image thereof;

FIG. 1.18 is a front view of an eighteenth image thereof;

FIG. 1.19 is a front view of a nineteenth image thereof;

FIG. 1.20 is a front view of a twentieth image thereof;

FIG. 1.21 is a front view of a twenty-first image thereof;

FIG. 1.22 is a front view of a twenty-second image thereof;

FIG. 1.23 is a front view of a twenty-third image thereof;

(Continued)

FIG. 1.24 is a front view of a twenty-fourth image thereof;
 FIG. 1.25 is a front view of a twenty-fifth image thereof;
 FIG. 1.26 is a front view of a twenty-sixth image thereof;
 FIG. 1.27 is a front view of a twenty-seventh image thereof;
 FIG. 1.28 is a front view of a twenty-eighth image thereof;
 FIG. 1.29 is a front view of a twenty-ninth image thereof;
 and
 FIG. 1.30 is a front view of a thirtieth image thereof.
 The appearance of the transitional image sequentially transitions between the images shown in FIGS. 1.1-1.30. The process or period in which one image transitions to another image forms no part of the claimed design.
 The display screen surface of the electric power socket track is illustrated by the black rectangular shape at the left. The broken lines and ghosted regions depict environment that forms no part of the claimed design.
